UNITED STATES PATENT OFFICE.

ALFREDO DONAGGIO, OF WINFIELD, NEW YORK.

SHIP SCAFFOLD.

Application filed May 6, 1921. Serial No. 467,351.

To all whom it may concern:

Be it known that I, ALFREDO DONAGGIO, a citizen of the United States, residing at Winfield, Long Island, in the county of 5 Queens and State of New York, have invented certain new and useful Improvements in Ship Scaffolds, of which the following is a specification.

My present invention relates to the staging or scaffolding used for the cleaning and painting of ships' hulls and is in the nature of an improvement on the scaffolding covered in my co-pending patent application 10 #360,681, filed Feb. 24, 1920.

15 The objects of this invention are to make the scaffolding more readily adaptable to fit the outline of the hull, to more firmly secure the scaffolding elements and to enable quick adjustments to keep the staging planks level.

20 Various other objects and special features of the invention will appear as the specification proceeds.

In the accompanying drawings forming 25 part of this specification, I have shown the apparatus embodied in one of its simplest forms, but wish it understood that the structure may be modified and changed without departure from the true spirit and scope 30 of the invention.

Figure 1 is a perspective view illustrating the application of the apparatus to a ship in dry dock.

Figure 2 is an enlarged broken plan view 35 illustrating the swiveling action of the staging sections or planks.

Figures 3 and 4 are bottom plan and edge views respectively of the swivel hook construction.

Figures 5 and 6 are side and plan views 40 respectively of one of the braces for supporting the scaffolding away from the hull.

Figure 7 is a broken detail illustrating features of adjustability of the scaffolding.

The scaffolding consists, as in my previous 45 application above referred to, of staging sections or planks, as they may be termed, 10, resting at their ends on the rungs 11 of flexible ladders 12 suspended in outstanding or edgewise relation at the side of the ship. 50 These planks are provided at their ends with members which hook over the rungs.

In Figures 2, 3 and 4 I have shown how 55 these hook members are specially constructed to permit the planks to be adjusted angularly with respect to the supporting rungs so as to fit them more closely to the hull,

particularly about the bow and stern. These members are illustrated as consisting each of a plate 13 secured to the under face of the plank by means of bolts 14 extending through arcuate slots 15, said plates having upwardly angled end portions 16 bearing against the correspondingly beveled end 17 of the plank and terminating in forwardly and downwardly projecting substantially 60 parallel hooks 18. The ends of these hooks are extended back closely adjacent to the angled portion 16 so as to leave in effect a narrowed throat 19 to admit the rung.

This requires a positive shifting of the 65 parts both to engage the hooks over the rungs and to disengage the hooks therefrom and hence avoids the possibility of accidental disengagement of the planks from their supports. The ends of the planks may be 70 curved, as indicated at 20 on an arc corresponding to the center 21 on which the arcuate slots are cut. This construction enables the planks to be swiveled with respect to their supporting hooks, as shown in Figure 75 2, and allows the curved beveled shoulders of the planks to have a bearing on the angled portions of the hook members irrespective of the angular relation of the hooks.

Along the sides of the ship the supporting 80 hooks may stand straight with the plank, as shown at the left in Figure 2, whereas at the bow and stern portions, the planks may be swiveled more or less to bring them into 85 approximate parallelism with the side of the ship at these points. One method of use is to accomplish this adjustment by first engaging the hooks over the rung and then after loosening the bolts, swinging the plank 90 to the desired angular relation and tightening the bolts to secure the parts in this adjusted position.

The several supporting ladders 12 may be raised and lowered by suitable suspension 95 cables 22 and to facilitate these raising and lowering adjustments, the rungs 11^a (Figures 5 and 6) which hold the ladders away 100 from the ship's side may each be provided with a pair of spaced rollers 23 bearing 105 against and riding over the side of the hull. For the purpose of mounting these rollers in spaced apart relation, I have shown the rungs 11^a as formed with Y-shaped extensions at the inner sides of the ladders having divergent arms 24 connected by a cross 110 bar 25 which forms the journals for the rollers. This spaced apart relation of the rollers

braces the ladders in edgewise outstanding relation to the hull and at the same time enables the ladders to be readily adjusted vertically.

5 In the illustration, the bracing rungs 11^a serve a further purpose, being provided at their outward ends with extensions 26 carrying loops 27 to receive a guard rope 28.

The bracing rungs may be interposed at 10 suitably spaced points in the ladders and for this purpose they are shown formed as rigid bars carrying blocks 29 provided with eyes 30 at the upper and lower sides thereof to receive the end links of the chains 31 constituting the flexible sides of the ladder.

To hold the ladders snugly against the side of the ship and to prevent them from swaying, means is preferably provided for securing the lower ends of the ladders in the 20 desired relations. In the illustration, I have shown such means provided in the form of longitudinally extending lengths of chain 32 provided at the opposite sides of the keel blocks and spaced at different distances therefrom, so as to provide convenient anchorages for the side chains of the ladders, which ladders I have indicated as having hooks 33 to be engaged over the anchorage chains. The anchorage chains 32 30 may be suitably secured at their ends to bolts, or otherwise fastened to the floor of the dock.

To provide a greater range of adjustability and to enable quicker adjustments being made, I may make the lower ends of the ladder chains variable in length by interposing sheaves 34 below the lower rungs over which pass chains 31^a forming in effect extensions of the side chains and terminating in hooks 35 which may be caught in the links of the chains at the points necessary to hold them taut. In using this construction, the hook 33 at the lower end of the inner side of the ladder will first be engaged with one of the anchorage chains 32 and then by pulling on the hook 35, the ladder will be drawn inwardly against the side of the hull, whereupon the hook 35 will be caught in the nearest link of the chain 31^a to secure the chain in this tautened condition. The same adjustment can then be made for the outer side of the ladder, the connection with the anchorage chain 32 being preferably made in this case so as to pull outwardly, as indicated in Figures 1 and 7. This spreading apart of the lower ends of the ladders braces them more firmly and overcomes edgewise swaying tendencies.

In the case illustrated, Figure 1 particularly, I have shown the rungs as of increased length toward the bottom of the ladder to increase the bracing effect obtained by a widened base.

The warping of the ladders in under the overhang of the hull has a tendency to

throw the rungs out of the horizontal and to overcome this, I propose to make one side of the ladder extensible and contractable, as shown particularly in Figure 7, that is, by interposing a sheave 36 over 70 which the lower section 31^b of the side chain passes, the same being adjusted and secured in the position necessary to hold the rungs horizontal as by means of a hook 37 engaged in the links of the chain. 75

My invention, it will be seen, makes it possible to adapt the scaffolding to suit practically any conditions and makes it possible to rig the staging with a minimum of labor and time. 80

What I claim is:

1. In scaffolding for ships' hulls, flexible ladders having rungs provided each with a horizontally disposed forked end projecting beyond the side of the ladder the 85 branches of the fork being disposed on opposite sides of the plane of the ladder and a plurality of hull-engaging rollers supported in spaced relation by said forked ends.

2. In scaffolding for ships' hulls, flexible 90 ladders having rungs provided each with a horizontally disposed forked end projecting beyond the side of the ladder, the branches of the fork being disposed on opposite sides of the plane of the ladder, a 95 pair of hull-engaging rollers supported in spaced relation by said forked ends and a cross bar connecting the forked ends and providing bearings for the rollers.

3. In ship scaffolding, staging sections 100 having base plates swiveled to the ends thereof, each having spaced hook portions for engagement with the rungs of a ladder.

4. In ship scaffolding, staging sections having base plates swiveled to the ends 105 thereof, each having spaced hook portions for engagement with the rungs of a ladder and means for securing said base plates in their angularly adjusted relations.

5. In ship scaffolding, staging sections 110 having base plates swiveled to the ends thereof, each having spaced hook portions for engagement with the rungs of a ladder and means for securing said base plates in their angularly adjusted relations, comprising securing bolts extending through the staging sections and base plates, the base plates having arcuate slots to receive said bolts.

6. In ship scaffolding, staging sections 115 having base plates swiveled to the ends thereof, each having spaced hook portions for engagement with the rungs of a ladder and means for securing said base plates in their angularly adjusted relations, comprising securing bolts extending through the staging sections and base plates, one of the parts through which said bolts extend having arcuate slots therein.

7. In ship scaffolding, staging sections 120

having curved and beveled end portions and supporting hooks swiveled to said staging sections and having angular shoulders bearing on said beveled end portions of the staging sections.

8. In ship scaffolding, staging sections having beveled end portions and supporting hooks swiveled to said staging sections and having angular shoulders bearing on said beveled end portions of the staging sections, the beveled end portions of the staging sections being curved substantially on arcs whose centers correspond with the swiveling adjustment of the supporting hooks.

9. In apparatus of the character disclosed, flexible ladders, means for holding the same outstanding edgewise away from the hull of a ship, staging sections supported by the ladders and means for anchoring the lower ends of the ladders with the sides thereof in widely spaced relation to thereby brace the flexible ladders and the staging sections carried by the same against edgewise swaying movement.

10. In apparatus of the character disclosed, flexible ladders, means for holding the same outstanding edgewise away from the hull of a ship, staging sections supported by the ladders and means for anchoring the lower ends of the ladders with the sides thereof in widely spaced relation to thereby brace the flexible ladders and the staging sections carried by the same against edgewise swaying movement, the ladders being constructed with rungs of greater length toward the lower ends of the same.

11. In apparatus of the character disclosed, flexible ladders, means for holding the same outstanding edgewise from the hull of a ship, staging sections supported by the ladders, means for anchoring the lower ends of the ladders with the sides thereof in widely spaced relation to thereby brace the flexible ladders and the staging sections carried by the same against edgewise swaying movement and to secure the same firmly against a ship's hull.

12. In apparatus of the character disclosed, flexible ladders, means for holding the same outstanding edgewise from the hull of a ship, staging sections supported by the ladders, means for anchoring the lower ends of the ladders with the sides thereof in widely spaced relation to thereby brace the flexible ladders and the staging sections carried by the same against edgewise swaying movement, and to secure the same firmly against a ship's hull, means for varying the length of one of the sides of the respective ladders to maintain the rungs of the same substantially horizontal.

13. In ship scaffolding, flexible ladders, means for holding the same spaced away from the hull of a ship, flexible anchorages

and flexible means between said anchorages and said ladders for securing the lower ends of the sides of the ladders to said flexible anchorages.

14. In ship scaffolding, flexible ladders, means for supporting the same outstanding edgewise and against the hull of a ship, flexible anchorages and means for securing the lower ends of the sides of the ladders to said flexible anchorages, said flexible sides of the ladders being independently adjustable to draw said sides taut with the ladders fitted to the contour of a hull.

15. In ship scaffolding, flexible ladders, means for supporting the same outstanding edgewise and against the hull of a ship, flexible anchorages and means for securing the lower ends of the sides of the ladders to said flexible anchorages, said flexible anchorages consisting of chains fastened at their ends and the sides of the ladders having hooks to engage said chains at different points in the length thereof.

16. In ship scaffolding, flexible ladders having means for spacing the same endwise away from the hull of the ship and having sheaves at the lower ends thereof and flexible means engaged over said sheaves for holding the ladders firmly against the ship's hull.

17. In ship scaffolding, flexible ladders having sheaves at the lower ends thereof, flexible means engaged over said sheaves, one of the side members of the ladder having an interposed sheave and a flexible connection passing thereover to provide for lengthening and shortening of said side.

18. In ships' scaffolding, a plurality of sections of chain adapted to be secured to the floor of a dry dock longitudinally thereof at opposite sides of the keel blocks and spaced different distances from said keel blocks at different localities longitudinally thereof and flexible scaffolding members adapted to be supported against the sides of a ship on the keel blocks and having means for attachment to said chain sections.

19. In ships' scaffolding, a plurality of sections of chain adapted to be secured to the floor of a dry dock longitudinally thereof at opposite sides of the keel blocks and spaced at different distances from said keel blocks at different points longitudinally of the dock and flexible scaffolding members adapted to be supported against the sides of a ship in the dock and provided with means at the lower ends of the same for adjustable engagement with said chain sections.

20. In ship scaffolding, a flat staging section and base plates swiveled on the flat side of said staging section at the ends thereof and provided with projecting hooks for engagement with the rungs of supporting ladders.

In testimony whereof I affix my signature.
ALFREDO DONAGGIO.
